GUN PORT

Filed Feb. 27, 1931

INVENTOR
Julius H. Wise
BY William Janus
ATTORNEY

UNITED STATES PATENT OFFICE

JULIUS H. WISE, OF ST. LOUIS COUNTY, MISSOURI

GUN PORT

Application filed February 27, 1931. Serial No. 518,737.

This invention relates to new and useful improvements in gun ports for use in banks and other places where a protected gun port in a wall is desired to permit the bank officials or other persons to protect themselves against bandits.

In banks, booths for armed guards, armored trucks, and other places it is desirable to have one or more gun ports located at strategic points whereby in case of a holdup or armed attack the bank employees or guards can defend themselves with guns without exposing themselves to the fire of the bandits.

However, in order to provide absolute protection to the armed employees and prevent surprise attack by the bandits by the latter taking advantage of the gun ports or apertures before said employees can make use of them, it is very essential that such gun ports be closed or sealed in such a manner that they can be opened only from the inside and can under no circumstances be pried or forced open from the outside or that side which is presented to the public.

To this end, the present invention contemplates the provision of a gun port having an aperture presented outwardly and provided with a closure member arranged adjacent to the inner side of said gun port and normally locked in closed position by suitable locking means arranged on the inside of said gun port and not accessible to the public.

Other objects of the invention are to provide a gun port provided with a gun aperture and having a closure plate movably mounted on the inside of said gun port for closing said aperture and movable laterally thereof into open position.

Still other objects of the invention are to provide a gun port comprising an outer member having a gun aperture and provided with a closure plate arranged adjacent to the inner side of said member and yieldingly held in closed position, there being a locking means provided for engaging said closure plate and locking it in closed position, said locking means being operable to release said plate by pressure applied to a part of said locking means arranged in exposed position on the inner side of said gun port.

Further objects of the invention are to provide a gun port comprising two flanged members which can be secured together and clamped against an apertured partition wall, the outer member being provided with an outwardly presented aperture, there being a closure plate arranged between said members and adjacent to said aperture for closing the latter, said plate being movable laterally past said opening whereby the barrel of a revolver can be presented outwardly through said aperture, there being suitable locking means arranged between said members for locking said plate in closed position, said locking means being partially exposed through said inner member so as to permit operation of said means by an authorized person to release said closure plate.

Additional objects of the invention are to provide an improved gun port of the class described which can be readily attached in position and can be securely locked against opening from the public side of the gun port and which can be readily operated from the inside by pressure applied thereto by means of the end of the barrel of the gun.

With these and other objects in view, my invention consists in certain novel features of construction and arrangement of parts, hereinafter more fully described and claimed, and illustrated in the accompanying drawings, in which—

Figure 1 is a front or outside elevational view of my improved gun port attached in position.

Figure 2 is a rear or inside elevational view thereof.

Figure 3 is an enlarged horizontal cross section taken on line 3—3 of Figure 2.

Figure 4 is an elevational view looking against the inner side of the inner member and showing the closure plate and the locking means mounted thereon.

Figure 5 is a horizontal cross section taken on line 5—5 of Figure 4.

Figure 6 is a detail cross section taken on line 6—6 of Figure 4.

Referring by numerals to the accompanying drawings, A indicates a bullet-proof wall having an aperture B which connects the cus-

5 tomer's side C of the wall with the inside of the enclosure or employee side D. The wall A is in the instant case formed of non-shatterable glass but may be of steel or other material.

10 A gun port 10 is located in said opening and permits projection of a gun from the enclosure so as to enable the employee to fire upon the bandits located on the other side of the wall without risk to his life.

15 This gun port consists of an outer member 11, an inner member 12, and a closure plate 14. Outer member 11 has a body portion 15 disposed in opening B. This body portion is in the shape of a truncated cone having an outwardly presented flared-out mouth 16, the inner end of which terminates in a central aperture 17.

20 The outer end of said body portion 15 terminates in a laterally disposed flange 18 which overlaps the outer end of said opening B and lies against the outside face of wall A. Preferably a gasket of felt or cork 19 is interposed between said flange and said wall to 25 form a seal therebetween.

30 The inner end of said body portion 15 has formed integral therewith a circular wall 20 disposed in vertical plane with said aperture 17. The outside diameter of this wall is less than the diameter of opening B so that said body portion 15 and said wall 20 can be easily inserted therein.

35 This wall terminates in an annular rearwardly presented flange 21 exteriorly threaded for receiving internally threaded annular flange 22 of inner member 12. The depth of flange 21 is such that a chamber E is formed between the spaced opposed faces of wall 20 and member 12 and the closure plate 14 is operatively arranged in said space. A set screw 40 23 is screw-seated in flange 22 and engages flange 21 and serves to lock the parts in assembled relation.

45 Flange 22 is of sufficient thickness to provide a bearing face 24 having sufficient surface contact with the inner face of wall A in opposed relation to flange 18 of the outer member 11. A gasket 25 of felt or cork is interposed between said wall and face 24 to insure proper seal therebetween. Thus the 50 gun port is supported in position by the clamping action of said flanges 18 and 22 and can be detached from the wall only from the inner side of said wall by the removal of inner member 12 and the outer face of said gun port is devoid of all securing or removable devices.

60 As stated before, closure plate 14 is disposed in chamber E between the vertically disposed opposed faces of inner member 12 and wall 20. This plate is pivotally mounted by a pin or screw 26 to the face of the inner member 12 and is movable laterally or edge-wise in said chamber E.

65 The inner member 12 is provided with an

70 elongated opening 27 having one end 27a formed of larger diameter than the aperture 17 and arranged concentrically therewith so that communication can be had through said apertures between the inner and outer sides of the wall. The other end 27b of said opening 27 is disposed to one side of the axis of the device and on a radial line therewith.

75 Closure plate 14 is formed with a straight edge 14a which when said plate is closed intersects said elongated opening 27 along a perpendicular line thereto and substantially equidistant from the ends thereof and well to one side of aperture 17 as indicated by line Y—Y in Figure 2. Thus with the plate 80 14 occupying closed position, only a smooth surface of said plate is exposed through aperture 17 as can be seen in Figure 1 while on the inner side, portion of said edge 14a is exposed through opening 27 as shown in Figure 2.

85 A spring 28 cooperates with said inner member 12 and with said closure plate 14 and urges the latter into closed position.

90 A plate 29 is pivotally mounted at 30 on the inner face of member 12 for swinging movement to and from said face. This member overlies the end 27b of said elongated opening and is provided with a straight edge 95 29a which is adapted to form an abutment or close contact with the straight edge 14a of closure plate 14 when the latter occupies closed position. Thus the contiguous portions of plate 14 and plate 29 are exposed on the inner side of wall A through the elongated opening 27 as shown in Figure 2.

100 A spring 31 bears against one side of said plate 29 and yieldingly holds the latter against the apertured wall of member 12. Preferably plate 29 is pivotally mounted on a block 32 and spring 31 is also secured at one end to said block and the latter in turn is secured to inner member 12 adjacent to the end 27b as shown in Figures 4 and 5.

110 Plate 29 is considerably thinner than plate 14 and is so mounted that when in normal position or spring-pressed against the apertured wall of member 12 that side of said plate which is arranged adjacent to the aperture 27 is disposed in the same plane with the corresponding face of the closure plate, the meeting edges 14a and 29a being flush. When, however, pressure is applied to said plate 29 through end 27b, as for instance, when the end of a gun is pressed thereagainst, said plate 29 yields, thereby exposing the edge 14a of plate 14. Now if pressure is applied by said gun to said edge 14a so as to overcome spring 28, said plate is caused to move edge-wise into a position shown in full lines in 125 Figure 4, thereby opening communication between apertures 17 and 27a so that the barrel of said gun can be thrust outwardly into the outwardly flared mouth 16. Thus the employee or person located on the inside of 130

wall A can aim his gun in any direction exteriorly of said wall without endangering his life.

The free end of closure plate 14 is provided with a radial extension 33 having a cam face 34 presented toward plate 29 and having a perpendicularly disposed face 34 presented in opposite direction. That end of plate 29 located adjacent to the free end of closure plate 14 is provided with a flange 36 which lies in the path of travel of extension 33 and terminates in a hook 37 adapted when the closure plate occupies closed position to engage the perpendicular face 35 and thereby lock said plate 14 in closed position (see Figs. 4 and 6). Thus under normal conditions closure plate 14 is locked in closed position and cannot be moved into open position until plate 29 is pressed inwardly so as to disengage hook 37 from the extension 33. Plate 29 is comparatively thin so that sufficient clearance exists in chamber E to permit this pivotal movement of plate 29 with respect to extension 33. The free end of plate 14 is provided near extension 33 with a projection 39 by means of which said plate can be moved manually when the inner member 12 is removed from its position on the outer member 10. Both plates 14 and 29 are mounted on the face of member 12, thereby facilitating the assembling of the parts and insuring proper operation thereof.

In order to strengthen outer member 10 a plurality of arms 40 is formed integral with and extends between the flanges 18 and wall 20.

The funnel or cone-shaped mouth 16 and the location of apertures 17 and 27 close together permits the barrel of the gun to be presented forwardly within said mouth and pointed in any direction at an angle of forty-five degrees to the axis of the device. Thus the gun can be swung readily into position at any point of a circle. This permits accurate aim of the gun and considerably insures the effective range of the gun.

I claim:

1. A gun port comprising a member provided with an outwardly flared aperture, said member having its outer end formed with a radial flange and its inner end with an annular flange, a closure plate operatively mounted adjacent to the inner side of said member and yieldably held in closed position, and a disk member detachably secured to said annular flange for enclosing said inner apertured end and said closure plate, said disk member being provided with an elongated slot, one end of which coincides with the inner end of said flared aperture, the other end extending to one side thereof so as to expose one edge of said closure plate.

2. A gun port comprising in combination an outer member adapted to be secured within an opening in a wall and provided with

an outwardly flared aperture, a closure plate operatively arranged adjacent to the inner side of said member for closing said aperture, a spring for yieldably maintaining said closure plate in closed position movable past said aperture to open the same, and means disposed inwardly of said member and engageable with said closure plate to lock it in closed position and an inner member secured to said outer member and enclosing said closure plate and said locking means, said inner member being provided with an elongated aperture, one end of which coincides with the inner end of said flared aperture and the other end extends to one side and exposes one edge of said closure plate and said locking means.

3. A gun port comprising in combination a member adapted to be secured within an opening in a wall and provided with an outwardly flared opening, a closure plate arranged inwardly of said member and adjacent to the restricted end of said opening and operable to open and close said aperture, and locking means arranged adjacent to the edge of said closure plate and cooperating therewith to lock it in closed position, said locking means being operable by pressure applied thereto to release said closure plate and permit the opening movement thereof by pressure applied to said edge of said closure plate.

4. A gun port comprising a member adapted to be secured within a wall opening and provided with a central outwardly presented aperture, a closure plate arranged adjacent to the inner side of said member for closing said aperture, and locking means operatively arranged adjacent to the inner side of said member for locking said closure plate in closed position, said means including a member arranged contiguous to one edge of said closure plate and displaceable by pressure applied thereto by the end of a gun barrel to actuate said means to release said closure plate whereby the latter can be moved into open position.

5. A gun port comprising a member having a central outwardly flared aperture, a closure plate pivotally mounted adjacent to the inner side of said member for closing the restricted end of said aperture, means for yieldably maintaining said closure plate in closed position, and a locking member arranged adjacent to one edge of said closure plate and adapted to engage the latter and lock it in closed position, said locking member being displaceable by pressure applied thereto to release said closure plate whereby lateral pressure can be applied to said edge to move said closure plate into open position.

6. A gun port comprising an outer member provided with an outwardly presented aperture, an inner member detachably secured to said first member and provided with

an elongated aperture, one end of which is coaxially arranged with the aperture of the first member, a closure plate operatively mounted between said members and closing the communication between said apertures, one edge of said closure plate being exposed through said elongated aperture, and a locking member operatively mounted between said outer and inner members adjacent to the exposed edge of said closure plate and adapted to engage the latter and lock it in closed position, said locking member being operable by the pressure applied to the exposed portion thereof through said elongated aperture to release said closure plate whereby pressure can be applied to the latter to move it into open position and establish communication between the apertures of said outer and inner members.

7. A gun port comprising an apertured member having an outwardly presented flared-out mouth, means for securing said member in position, a closure plate movably mounted adjacent to the inner side of said aperture for opening and closing the same, and locking means arranged adjacent to said closure plate and engaging the latter and locking it in closed position, said locking means being displaceable by the pressure applied thereto by the end of a gun to release said closure plate and permit opening of same.

8. In a device of the class described, an outer member having a forwardly presented cone-shaped cavity terminating at its inner end in an aperture, a closure plate arranged adjacent to the inner side of said outer member for closing said aperture, means for supporting said closure plate for movement laterally past said aperture, means for yieldably maintaining said closure plate in closed position, locking means arranged adjacent to the inner side of said outer member and in co-operate relation with said closure plate for locking the latter in closed position and operable by pressure applied thereagainst to release said closure plate and expose one edge thereof whereby said plate can be moved into open position by pressure applied to said edge.

9. A gun port comprising an outer member having an outwardly flared cavity, the inner end of which terminates in an aperture, an inner member secured to and arranged in spaced relation with the first member and provided with an elongated aperture, one end of which is concentrically arranged with the first aperture, a closure plate movably mounted between said members for closing the communication between said apertures, a locking plate movably mounted between said members adjacent to said closure plate, and adapted to engage the latter and lock it in closed position, said locking plate being displaceable to release said closure plate whereupon the latter can be moved into open position.

10. A gun port comprising an outer member having an outwardly flared cavity, the inner end of which terminates in an aperture, an inner member detachably secured to said first member in spaced relation therewith to provide a chamber, said inner member being provided with an elongated aperture, one end of which is concentrically arranged with the first aperture, a closure plate movably arranged in said chamber for closing the communication between said apertures, one edge of said closure plate being exposed through said elongated aperture, and a locking plate movably mounted in said chamber adjacent to the edge of said closure plate, said locking plate being displaceable by pressure applied thereto to expose the edge of said closure plate whereby the latter can be moved by pressure applied to said edge remotely with respect to said apertures so that a gun can be thrust outwardly through said apertures and through said flared-out mouth.

In testimony whereof I hereunto affix my signature this 24th day of February, 1931.

CERTIFICATE OF CORRECTION.

Patent No. 1,847,419.

Granted March 1, 1932, to

JULIUS H. WISE.

It is hereby certified that error appears in the printed specification of the above numbered patent requiring correction as follows: Page 3, line 69, claim 2, beginning with "a spring" strike out all to and including the word "and" in line 71, and insert instead and movable laterally past said aperture to open the same, a spring for yieldably maintaining said closure plate in closed position; and that the said Letters Patent should be read with these corrections therein that the same may conform to the record of the case in the Patent Office.

Signed and sealed this 5th day of April, A. D. 1932.
